UNITED STATES PATENT OFFICE

2,430,431

AIRPLANE WING LIFT MODIFICATION

Edward M. Lanier, Newark, N. J., assignor to
 Lanier Aircraft Corporation, Bristol, Pa., a corporation of New Jersey

Application March 12, 1943, Serial No. 478,932

3 Claims. (CL. 244—40)

1

The present invention relates to means for increasing the lift and flying qualities of an airfoil and it particularly has for its object to provide means to increase greatly the lift of an airplane at slow speeds without increasing the wing area; to provide means by virtue of which quicker take-offs, faster climbs, slower landing speeds and higher top speeds can be attained than by the present types of planes.

More specifically the invention has for an object to improve the planes of the type disclosed in the United States Patent to Edward H. Lanier, reissued August 13, 1935, Re. No. 19,665.

Another object of my invention is to provide a plane of the above mentioned Lanier type with means by which the cellules may be provided with a top closure that can be put in place after the plane is in the air when it may become desirable to close the cellules.

A further object is to provide, what I may term, an artificial slip stream of air over the airfoil while the plane is at rest, during the take-off and landing, which will be particularly valuable not only in powered aircraft but in gliders also, as it may be set up independently of a driving propeller.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, and then be particularly pointed out in the appended claims, reference being made to the accompanying drawings, in which:

Fig. 1 is a top plan view of an airplane of the Lanier type hereinbefore referred to.

Fig. 2 is a detail section on the line 2—2 of Fig. 1.

Fig. 3 is a diagrammatic view of one method of utilizing my invention.

Fig. 4 is a view similar to Fig. 2, on a somewhat larger scale, showing how the invention, in one of its aspects, may be applied to airfoils having very shallow cellules.

Fig. 5 is a view similar to Fig. 4, but showing how a top for the cellule may be employed with means to lower and raise it as desired.

Fig. 6 is a view similar to Fig. 2, but omitting the air tubes or ducts, circular plate heaters being indicated within the cellule.

Figs. 7 to 10 inclusive are detail cross-sectional views showing different outlets for the air tubes or ducts.

2

Fig. 11 is a detail plan view of a wing having an airfoil of relatively large area and indicates several different forms of heaters that may be separately or collectively employed.

5 Fig. 12 is a section of an airfoil similar to Fig. 5, showing another modification of the top or cellule cover lifting mechanism.

Fig. 13 is a sectional view of a further modification of the invention.

10 Fig. 14 is a detail plan view of a cellule showing a modified means to close the top of the same.

Fig. 15 is a section on the line 15—15 of Fig. 14.

Fig. 16 is a view similar to Fig. 3 but showing a modification thereof.

15 Fig. 17 is a view similar to Fig. 4 but showing a modification wherein the air ducts or tubes lie on the top face of the airfoil.

Fig. 18 is a view similar to Fig. 17, showing a modification of the same.

20 In the accompanying drawings, in which like numbers and letters of reference indicate like parts in all the figures, 1 is the body of the plane, 2 the wings, 3 the cellules or vacuum chambers, and 6 the spars.

25 The wings have closed bottoms, as at 4. The tops of the wings, except for the cellules, are closed as at 5, 5^x. Following the contour of the top surfaces of the wings and crossing the cellules are streamlined air ducts 7 having rearwardly directed outlets which may be continuous slits 21^a,

30 Fig. 7, a series of holes 21^b, Fig. 8, or any other suitable shapes, and the outlets of the ducts (7, 7^x, 7^y, 7^z) may have the cross-sectional form of either Fig. 7, Fig. 8, Fig. 9, or Fig. 10, as found 35 most effective in practice.

In Fig. 2 there is indicated a heater surface 29 on the bottom of the cellule. In Fig. 5 the wall 16 has heating elements 20^b. In Fig. 6 the heating elements are individual members 20^c. The

40 heating elements may be of any approved kind and of desired shape or form. In Fig. 11 three different forms of heating elements are indicated, namely: short rectangular heaters 20^e, long rectangular heaters 20^d, and individual circular heaters 20^f; any style or all styles may be used as found most convenient.

The fluid for creating the artificial or auxiliary air streams via the tubes or ducts 7 may be obtained in any desired way. Preferably, I provide 50 a tank 11 for storing compressed air, see Figs. 3 and 16. The tank may be charged and kept charged in any suitable way, as for example by means of a motor or engine-driven compressor 13 which takes in air through an opening 14 in the body 1 and passes it through a back check valve

12 into the tank 11 from which it is delivered as required via a manually controlled valve 10 and ducts 9 and 8 to the ducts 7, see Fig. 3. As shown in Fig. 16, the ducts 7^e have individual valves 10^e to control the velocity of the gaseous fluid from each duct 7^e so as to create a smooth high velocity flow over the entire surface.

Referring now to Fig. 5, it will be seen that the cellule 3 is provided with a top 16 that can be raised into place or lowered to the bottom of the cellule, or located at any desired intermediate position. This top 16 has transverse grooves 15 to receive the ducts 7^b when the top is closed.

Any suitable mechanism may be provided for mounting and for raising and lowering the top 16. For example, in Fig. 5 I have, somewhat diagrammatically, shown cylinders, pivoted at 19, and having pistons (not shown) whose rods are connected to links 17 that are in turn connected with the floor of the cellule (bottom of the wing) and with the top 16 in such manner that when the pistons are forced out by fluid pressure in the cylinders (admitted thereto by suitable means, not shown, under control of the aviator) the links will raise the top into place, and conversely as the pistons recede the links will lower the top to the place desired.

In Fig. 12 screw jacks 23, 24 are shown for lifting and lowering the cover 16^d, the jacks being operated by means of a worm shaft 25 and 26, the latter extending into the body 1^d to a convenient place for operation by the aviator.

In the modification shown in Fig. 12, 22 designates the cap strip of the bulkhead which is fixed as to position, and 39 indicates the bulkhead diagonals.

In the modification shown in Fig. 13, the cellule top 16^e is hinged, as at 27, at the aft end and may be raised and lowered by a cylinder and piston device 18^e, or other suitable means.

In the modification shown in Figs. 14 and 15 the cellule 3^f extends to the aft edge of the wing or airfoil 2^f and the cover is made in two major parts, one of which embodies the aft section 5^f which is hinged at 34 and is secured to a rotatable shaft which has a gear 35 meshing with a worm 36 on a shaft 37 that is operated by a hand wheel 38 located in the body of the airplane; the other part is composed of hinged shutters 28 on rods 29 which have gears 30 that mesh with worms 31 on worm shaft 32 that has a hand wheel 33 for operation by the aviator.

In Figs. 4, 5 and 6 and in Figs. 12 to 15 inclusive, those parts which correspond to like parts in Figs. 1 and 2 bear the same reference numerals plus the index letter "a" (Fig. 4), "b" (Fig. 5), "c" (Fig. 6), "d" (Fig. 12), "e" (Fig. 13), and "f" (Figs. 14 and 15), respectively. In Fig. 17 those parts which correspond to like parts in Fig. 4 bear the same reference indicia plus the prime mark. In Fig. 18 the parts which are the same as those in Fig. 16 bear the same reference indicia as in Fig. 4 plus the double prime mark, 20^a indicating heaters.

It is a well known fact in aerodynamics that as the velocity of air is increased over an airfoil, the pressure on the top surface will decrease; and naturally the lower the pressure on the top of the airfoil the higher the lift will be. Lift is produced on an airfoil by the forward motion of the airplane moving through the fluid (air) and causing a diversion of the airflow to produce a negative pressure on the top and a positive pressure on the underside of the airfoil. As the speed of the airplane increases, so does the velocity of the airflow over the airfoil. The smoother the flow,

the higher the velocity. The greater the velocity, the higher the lift.

In my invention lift is not totally dependent upon forward speed or motion of the airfoil moving through the air. With my invention embodied in an airplane, a considerable degree of negative pressure can be produced on top of the airfoil while the plane is at rest on the ground. This adds greatly to the quick lift of the plane as it starts over the ground and also enables the plane to land in a much smaller area than would be the case were my invention not used.

From the foregoing it may readily be seen that the result will be a plane of greater load carrying capacity, reduced takeoff and landing speeds, or smaller wings, increased speeds, etc. The boundary layer flow should be favorably influenced so as to reduce drag and increase the burble point. The speed should also be greatly increased due to the practicability of using an airfoil section with extremely low drag characteristics.

The streamlined tubes 7 may be made of steel, dural, wood-plastic, plastic, or like material. The number to be used in any given installation and the proper distances apart will be determined by tests well within the skill of the aviation engineer.

The compressed air flowing from the tubes flows the length of the chord from the front of the airfoil rearwardly, creating a negative pressure on the topside of the airfoil over the cellules, thereby creating suction lift according to the degree of negative pressure created. The degree of negative pressure is dependent upon the velocity of the air or gas flowing from the tube outlets. In practice it is preferable that the velocity of the fluid issuing from ducts 7 be so equalized in each jet, as to make a smooth flow moving from fore to aft of the airfoil.

By heating the air in the cellules, or topside of the airfoils, the molecules of air are split, thus making the air lighter. This lighter air is easier to move by suction than heavy cool air, and a faster and greater reduction of the pressure on the top side of the airfoil is the result.

If desired, the jets and heat need not be operated except for take-offs and landings.

My invention is adaptable to all shapes and aspect ratios of wings.

The pressure to create the tube jet velocity may be made either by the use of a gas-mixing chamber and pressure valves connected to the tubes, or by using an air scoop in front of the plane, preferably at the front of the motor, or by the means hereinbefore referred to and illustrated in Fig. 3. The compressed air in the tank will allow landings to take place without the main motor running.

From the foregoing description, taken in connection with the accompanying drawings, it is thought that the complete construction, operation and advantages of my invention will be clear to those skilled in the art.

What I claim is:

1. In an airfoil having a closed bottom face, a covered nose and an open top chamber to the rear of said nose, a set of air ducts extending across the line of flight over said chamber and having rearwardly directed outlets, a top for said chamber, and means for raising and lowering said top to effect, respectively, the opening and closing of said chamber, said top having recesses to receive said ducts when the top is in place.

2. In an airplane having a body and wings, the latter being provided on their upper sides with open top chambers each chamber extending

from the nose to adjacent the trailing edges of the wings, a reservoir for compressed gaseous fluid, means for supplying the reservoir with such fluid, and manually controlled means for delivering the gaseous fluid from said reservoir in the form of a slip stream over the tops of said chambers in a fore and aft direction, said means including ducts extending across the chamber and lying in the general contour of the top faces of the wings, said ducts having rearwardly directed outlets. 10

3. In an airplane having a body and wings, the latter being provided on their upper sides with open-top chambers each chamber extending from the nose to adjacent the trailing edges of the wings, a reservoir for compressed gaseous fluid, means for supplying the reservoir with such fluid, and aviator-controlled means for delivering the gaseous fluid from said reservoir in the form of a slip stream over the tops of said chambers in a fore and aft direction, said means including ducts extending across the chambers and lying in the general contour of the top faces of the wings, said ducts having rearwardly directed outlets, those of one duct being directed so as to add the air stream of that duct to the air stream of the next succeeding duct. 15 20 25

EDWARD M. LANIER.
